COMBINATION STOOL AND STEPLADDER

Everett M. Keen, Vineland, N. J.

Application September 16, 1944, Serial No. 554,468

8 Claims. (Cl. 155—42)

1

The present invention relates to furniture and more particularly to a stool or chair adapted especially to household use. While a number of novel and useful features are provided by the invention, a preferred form of construction comprises a device which combines the functions of a stool and a step ladder. In such complete realization of all the principal objects of the invention the structure is useful in households, and particularly in the kitchens thereof, as an ordinary stool on which a person may sit at a table, sink or the like, and as a step ladder on which a person may stand high enough above the floor for such varied purposes as reaching the ceiling to wash or paint it, reaching the top shelf of a cupboard or cabinet, or reaching a ceiling lighting fixture to change the bulb.

To accomplish these and other related objects, the construction in its preferred forms of embodiment comprises a generally rigid frame structure including a seat and a plurality of legs. Movable mounted in the frame is step means, comprising a single individual step or a pair or more of individual steps, which step means is normally maintained in retracted position beneath the seat of the stool but which can be projected forwardly to serve as the tread means of a step ladder. When, as is preferred, two or more of such individual steps are incorporated in the structure, they are made separately extensible to different limits, so that the lowermost step will project farther from the plan projection of the seat than the higher step or steps. The result is a more or less regular backward incline of the front edges of the extended steps and the seat, so that all these elements cooperate in the manner of a step ladder to make ascent and descent very easy and safe.

An important object of the invention is to provide strong and stable support for the step means when extended and to keep the center of gravity of all loads on the seat or on any step always well within the polygonal outline which includes the points of contact of the legs on the floor. Specifically this is accomplished by providing the lowermost step with legs which move with it to extended position, so that the support outline becomes appropriately enlarged for step ladder use of the structure, and by limiting extension of the upper step means so that none of them can project as far as the extended legs of the lowermost step.

Further objects are concerned with making the appearance of the structure neat and ornamental, making the construction rugged and du-

2

rable, reducing the cost of manufacture, rendering all the moving parts easily operable and fool-proof, and making it possible to construct the entire device from standard gauge sheet metal stock.

With these and other objects in view, as will more clearly appear to those skilled in the art from a reading of the present specification, the invention comprises, in a preferred form of embodiment which has been actually made and been found entirely satisfactory in service, the construction illustrated in the accompanying drawing and described hereinafter.

But this construction is selected merely to illustrate the broad principles of the invention as defined in the appended claims. Various details may be modified or eliminated, all within the spirit of the invention which is defined by the claims. Hence these claims are intended to be construed broadly and without limitation except as required by their express wording or by the state of the prior art.

In the drawing, in which the same reference character designates the same part in the several views,

Fig. 1 is a perspective view showing the step means of the combination device extended so that the device will function as a step ladder;

Fig. 2 is a similar perspective view showing the step means retracted for use of the device as a stool;

Fig. 3 is a vertical cross-sectional view taken substantially midway between the front and rear legs of the device, looking backward toward the rear legs;

Fig. 4 is a horizontal cross-sectional view taken through an upper step, along the line 4—4 of Fig. 3, looking downwardly;

Fig. 5 is a horizontal cross-sectional view taken through the lowermost step, along the line 5—5 of Fig. 3, looking downwardly;

Fig. 6 is a vertical cross-sectional view taken substantially midway between the front and rear leg members, along the line 6—6 of Fig. 3, looking to the left in that figure and showing the step means extended;

Fig. 7 is a view similar to Fig. 5 showing a modification; and

Figs. 8 and 9 are detail views showing a further modification.

The device comprises essentially a rigid frame comprising a plurality of leg members supported by and supporting a seat. In the illustrated embodiment four leg members are used. These comprise two rear legs 10, 10 and two front

leg members 11, 11. The elements 10 and 11 have rigidly secured to their upper ends, as by the nut and bolt means 12, or by spot welding or otherwise, a seat element 13 to which may be secured a conventional type of backrest 14 conveniently provided with a hand hold opening 15 by which the device may be lifted and carried.

While all these parts of the structure may assume any appropriate form, I find it convenient to make the leg elements of angle iron stock, or better still of sheet metal formed in angle shape, and to make the seat element from sheet metal, generally rectangular in plan but with rounded corners, and having a down turned peripheral flange 16. This flange provides a convenient inner surface against which the side and front or rear flanges of the angle leg elements may be engaged and to which they may be secured by the nut and bolt means 12 or otherwise as has been explained.

The backrest 14 is best made of sheet metal, appropriately curved and trimmed, and bolted or otherwise secured at its bottom margin to the flange 16 of the seat member.

The rear legs 10 are of full length, extending from the floor level to their connection with the seat element, but each of the front legs 11 is formed in two sections 11a and 11b, for a purpose which will presently appear.

The upper front leg sections 11a constitute parts of the rigid frame. They are connected to the rear legs 10 by upper side braces 17 and lower side braces 18 which perform the function of ordinary chair rounds. The upper side braces 17 are connected together by a cross brace 19 and the lower side braces are connected together by a cross brace 20. The preferred forms of these several bracing members will now be explained.

In addition to their rigidifying function in the frame, the side braces 17 and 18 are required to serve as guideways for sliding steps, and each of them is therefore made of channelled stock, conveniently sheet metal formed with a central web 21 and top and bottom flanges 22. The channels face inwardly and they may be secured to the leg members by welding their webs to the leg member side flanges or, as is shown in the drawing, by striking portions of the channel flanges up and down respectively at the ends of the channels to form fastening ears 23 which are bolted or spot welded to the leg member front and rear flanges with which they are engaged.

The cross braces 19 are best made in the form of simple plates each having a central stiffening rib 24.

In the illustrated embodiment I have shown a single pair of upper side braces 17 and a single pair of lower side braces 18, but it will be understood that more may be provided, if desired, in any larger embodiment of the invention.

The upper sections 11a of the front legs terminate at substantially the level of the upper flanges 22 of the lower side braces 18. These lower side braces terminate forwardly at about the line of the rear edge of the side flange of each of these upper leg sections 11a. In order to secure the lower ends of the upper leg sections 11a to the lower side braces 18, I may use gusset plates 25, each having an inturned lower flange 26 secured to the upper flange 22 of the adjacent side brace 18 and having its web secured to the side flange of the adjacent upper leg section 11a, as is clearly shown in Figs. 1 and 2.

The structure thus described provides a very rigid frame, even when made of comparatively light gauge sheet metal, as is preferred.

In the illustrated embodiment of the invention two movable steps are provided. The lowermost of these, designated 27, will now be described. It comprises a flat tread portion made generally like the seat element 13, out of sheet metal provided with a downturned peripheral flange 28. This step 27 is arranged to slide in and out in the guideways formed by the facing channel shapes of the lower side braces 18. It is also provided with supporting means in the form of the lower front leg sections 11b. Thus it may be retracted in the guideways, as shown in Fig. 2, to adapt the structure for use as a more or less ordinary stool, or it may be extended, as shown in Fig. 1, to adapt the structure for use as a step ladder. In the retracted position the leg sections 11a and 11b are vertically aligned, while in the extended position, as shown in Fig. 1, the lower front leg sections 11b are forwardly offset from the upper sections 11a, thus providing good stable support for the structure and any load that may be imposed on it.

While the lower step can be made in a number of ways, I prefer to make it as shown in the drawings. This construction consists in making the tread portion substantially rectangular in plan, although its front edge may be somewhat rounded to enhance its appearance. Extending along each of the right and left sides of the tread portion 27 and parallel to the flange 28 thereof is a runner 29 comprising a strip of sheet metal of specially formed shape. The rear end portion 30 of each of these runners is secured to the rear peripheral flange 28, and thence the runner extends outwardly a short distance beyond the tread portion of the step and is turned forwardly to extend along the side of the tread portion parallel to the side flange 28. Just short of the front edge of the tread portion the runner is turned right angularly inwardly to provide a shoulder 31 and meet the flange 28. The runner is then continued a short distance around the front of the step, in contact with the front flange 28 thereof, to terminate short of the center of the front flange in a portion which is bolted or otherwise secured thereto, as shown at 32. Some such spacing means as the element 33, best shown in Fig. 5, may, if desired or thought necessary, be secured between the side flange 28 and the runner 29 to stiffen the relation of the two members and keep them accurately parallel.

The upper end of each lower front leg section 11b is engaged with the shoulder 31 of the runner 29 and fixed thereto by bolting or otherwise. If desired or thought necessary, a small spacer plate 34, see particularly Fig. 5, may be inserted so that when the lower step assembly is in the retracted position shown in Fig. 2 the two front leg sections will be accurately aligned.

As will be evident from the drawing, the lower step assembly slides in the channel guideways provided by the lower side braces 18. The side projections formed by the runners 29 fit in the channels with sufficient play to permit easy sliding but with enough penetration to prevent separation. To limit the extent to which the lower step assembly may be slid forwardly from its guideways I provide a pair of registering perforations in the flanges 22 of each side brace member 18 and drop a bolt 35 through them. This bolt becomes engaged by the outwardly extended rear portion 30 of the runner when the

assembly is slid forward and thus limits the extent of forward movement.

It will be evident from the foregoing that the lower step may be readily moved between its Fig. 1 and Fig. 2 positions to convert the structure from step ladder to ordinary stool use. Any weight imposed on the lower step when in extended position is borne by the rear legs 10 and the front leg sections 11b and is transmitted to the floor, the center of gravity of the construction being well within the outline which includes the points of contact of these legs and leg sections on the floor. Thus the device is perfectly stable.

A second step, or a plurality of steps, is best provided. In the illustrated embodiment a single upper step is shown mounted to slide in the guideways provided by the single pair of upper side braces 17. This upper step, designated 36, is made much like the lower step 27, being provided with a similar runner 37 on each side, stiffened if desired with relation to the flange 38 by the element 39. The runner 37 is turned in to engage the flange 38 and provide a shoulder 40, but this shoulder is spaced relatively far back along the side of the step 36 as compared with the position of the shoulder 31 of the lower step 27. The result is that the runner and the guideways provided by the upper side braces 17 interfit to permit the upper step to be slid in and out a distance which will be limited by engagement of the back of the step with the rear legs when the step is in retracted position and by engagement of the shoulder 40 with the front flanges of the front legs when the step is in extended position. Since the channel guideways provided by the upper side braces 17 are closed at their front by the front flanges of the upper sections 11a of the front legs, it is unnecessary to provide any such slide-limiting means as the bolts 35.

If desired or thought necessary, the front flanges of the upper leg sections 11a may be slightly notched as shown at 42 to pass the forward end portions of the runner 37, so that these portions may end along the front of the flange 38 and be secured thereto in stiffening relation, like the portions 32 of the lower step runners 29.

The two or more steps are so arranged that their stops (the bolts 35 and the shoulders 40) permit the upper step 36 to be extended only about half as far as the lower step 27. Thus the several steps, when extended, have their front edges arranged in a more or less regular backward incline toward the front edge of the seat element 13. In this position of the parts the structure provides a very useful step ladder, as has been explained hereinabove. When the steps are all retracted, they are all out of the way in the frame, substantially within the plan projection of the seat element, and the front leg sections are vertically aligned, so that the device may be used as an ordinary kitchen or other type of stool, with the step ladder parts in no way interfering with the legs of a person sitting on the seat element.

Fig. 7 shows a slight modification in which the forward end portions 32 of the runners 29 of the lower step assembly are fastened to the inside surface of the flange 28 of the lower step member 27 instead of to the outer surface thereof as shown in Figs. 1 and 2. In the Fig. 7 form the flange 28 is slotted at 43 to pass the runner. This construction affords all the rigidity of the arrangement shown in Figs. 1 and 2 and may by some designers be considered as producing a somewhat

neater appearance because it masks the front edges of the runners. Of course this same modification may be made in respect of the upper step, and Fig. 7 is therefore intended to serve as a view of a variation of Fig. 4 as well as of Fig. 5.

Figs. 8 and 9 show one type of further modification which can be employed if it be thought necessary or desirable to latch either or both of the steps in extended position to prevent their accidentally being moved back to retracted position and to increase their sliding friction in the guideways so that they are not apt to fall forward to extended position if the stool is picked up and tilted forward. Such latches may take any one of a number of forms, but I have found the one illustrated in Figs. 8 and 9 to be simple, inexpensive and entirely practical and satisfactory. It consists of a small spring finger riveted or otherwise secured at its lower end to the inner surface of one of the two runners 29 of the lower step (or to the inner surface of one of the two runners 37 of the upper step). The upper end of this finger is bent inwardly and provided with a button 46, preferably having a beveled face, pressed by the spring tension of the material of the finger into frictional engagement with the under surface of the top flange 22 of the upper side brace 17 or of the lower side brace 18, as the case may be. This surface is provided with the aperture 47 into which the button snaps when the step is in fully extended position, so that the step is thereby latched. Retraction of the step requires the button to be pushed down through the aperture sufficiently for its beveled face to cam the button entirely through the aperture when the step is pushed back toward retracted position. When in retracted position the friction of the button on the flange 22 is sufficient to hold the step in place even though the stool be tilted forwardly to fully horizontal position.

When this or any any other type of latch is associated with the lower step, one or both of the stops 35 may be omitted or, if desired, both stops 45 can be retained. In such case, of course, the stop and the latch will be so located adjacent to a single runner 29 that neither will interfere with the other.

It is thought that from the foregoing it will be evident to those skilled in the art that the present invention attains all the objects and purposes set forth in the introduction to this specification of the details of a practical embodiment which has been manufactured and has given complete satisfaction in actual use.

It will be understood that the construction readily lends itself to finishing by painting, enameling or plating in the usual way for metal furniture. In this connection I wish to point out particularly that none of the parts which are in sliding contact (and which therefore would not very long maintain unmarred a coating of paint or the like) is exposed to view when the parts are retracted and the structure is in position for use as a stool, as shown in Fig. 2. For example, the tread portions of the steps are spaced by the runners 29 and 37 from the channel guideways, so that the finish of these tread portions is protected from contact with the guideways. The runners may be left unfinished for good sliding contact with the guideways, particularly since they are entirely concealed in the normal position of the parts. I regard this as an important 70 feature of the invention.

I claim:

1. A combination stool and step ladder comprising a plurality of leg members including two rear leg members and two front leg members, the front leg members being divided into upper sections and lower sections, means connecting the rear leg members and the upper sections of the front leg members to provide a rigid frame, a seat surmounting and supported by said frame, and a step slideable in the frame and secured to the lower sections of the front leg members and extensible from the frame with said lower sections so as to be supported thereby in extended position.

2. A combination stool and step ladder comprising two rear leg members and two front leg members, the front leg members being divided into upper sections and lower sections, means connecting the rear leg members and the upper sections of the front leg members to provide a rigid frame, a seat surmounting and supported by said frame, and means connecting the lower sections of the front leg members to the frame for movement from a retracted position aligned with the upper sections to an extended position forwardly offset therefrom, said means including a step secured to the lower sections and slideable in the frame.

3. A combination stool and step ladder comprising two rear leg members and two front leg members, the front leg members being divided into upper sections and lower sections, oppositely facing horizontal channel members connecting the rear leg members and the upper sections of the front leg members to provide a rigid frame having a pair of guideways formed by the channel members, a seat surmounting and supported by said frame, and means connecting the lower sections of the front leg members to the frame for movement from a retracted position aligned with the front sections to an extended position forwardly offset therefrom, said means including a step secured to the lower sections and slideable in said guideways.

4. In a combination stool and step ladder, a frame including a pair of front leg members divided into upper and lower sections and a pair of rear leg members, means mounted in the frame for sliding the lower sections forwardly to a limited extent from aligned relation with the upper sections, said means including oppositely facing channel guideways mounted in the frame and a tread member slideable in the guideways and connecting the lower sections of the front legs and adapted to act as a lower step supported by said lower sections when slid forwardly, an upper step slideable forwardly from the frame and adapted to transmit load down through the frame to points on said guideways and thence to the rear legs and the lower sections of the front legs, and means limiting the forward sliding movement of the upper step to an extent less than the full forward position of said tread member.

5. A combination stool and step ladder comprising a plurality of leg members secured together so as to provide a rigid frame, a seat surmounting the frame and supported thereby, a pair of guideways in the frame below the level of the seat, a step mounted in the guideways for sliding movement between a retracted position substantially covered by the seat and an extended position beyond the plan projection of the seat, and means

holding the step in retracted position comprising a resilient finger moving with the step and frictionally rubbing one of the guideways.

6. A combination stool and step ladder comprising a plurality of leg members secured together so as to provide a rigid frame, a seat surmounting the frame and supported thereby, a pair of guideways in the frame below the level of the seat, a step mounted in the guideways for sliding movement between a retracted position substantially covered by the seat and an extended position beyond the plan projection of the seat, and means holding the step in either of said positions comprising a resilient finger moving with the step and frictionally rubbing one of the guideways when the step is being moved to retracted position and adapted to snap into an opening formed in the guideway when the step is in extended position.

20 7. In a combination stool and step ladder, a pair of front leg members divided into normally axially aligned upper and lower sections, a rigid frame including said upper sections and a rear support, a tread member rigidly connecting the lower sections and having its front portion supported thereby, and means slidably mounting the tread member in the frame for limited forward movement to a position in which the lower sections are forwardly offset from the upper sections and 25 the rear portion of the tread member is held within the frame and is supported by said rear support.

30 8. In a combination stool and step ladder, a pair of front leg members divided into normally axially aligned upper and lower sections, a rigid frame including said upper sections and a rear support, a lower tread member rigidly connecting the lower sections and having its front portion supported thereby, means slidably mounting said 35 tread member in the frame for limited forward movement to a position in which the lower sections are forwardly offset from the upper sections and the rear portion of the tread member is held within the frame and is supported by said rear support, an upper step forwardly slidably mounted in the frame between the upper sections, and means limiting forward sliding movement of the 40 upper step to an extent less than the full forward position of the lower tread member, said upper step being adapted to transmit load down through the frame to said rear support and said 45 lower sections.
